F. BOLINSKI

RIBBER MACHINE ATTACHMENT

Filed April 25, 1925

Felix Bolinski
INVENTOR
BY *Victor J. Evans*

WITNESS:

Walter Bolinski

ATTORNEY

UNITED STATES PATENT OFFICE.

FELIX BOLINSKI, OF PINCKNEYVILLE, ILLINOIS.

RIBBER-MACHINE ATTACHMENT.

Application filed April 25, 1925. Serial No. 25,858.

This invention relates to new and useful improvements in knitting machine attachments and more particularly to an attachment for that type of machine which is known as the ribber machine for knitting stockings. The main object of my invention is the provision of an attachment which constitutes a stop motion cooperating with the third yarn on a ribber machine whereby when the third yarn runs out or breaks the machine will be stopped to avoid waste.

Another object of my invention is the provision of an attachment of the above character which may be quickly and readily applied to the class of machine set forth and wherein the breaking of the third yarn or the running out of the same will operate a trip which will cut off the power for the main machine.

With the above and other objects in view, my invention consists in the novel features of construction and the combination and arrangement of parts to be hereinafter more fully described, pointed out in the claim and shown in the accompanying drawing, in which:

The figure illustrates a side elevation of my improved attachment, parts thereof being broken away and illustrated in cross section.

Referring more particularly to the drawings, the numeral 1 indicates a substantially rectangular frame having spaced guides 2 at one side thereof through which the usual knitting yarns 3 pass. These yarns 3 are the main yarns used in the knitting machine and the third yarn is supplied to the knitting machine thru the guide tube 4 at one side of the frame and a portion of the yarn passes over a bifurcated guide 5 prior to passing thru the tube 4 has alternately passed thru the guide loops 6 carried by the frame.

The supply 7 for the third yarn is rotatably mounted upon the lower portion of the frame and the strand from the supply extends upwardly thru the guide 8 positioned beneath the supporting arm 9 which extends inwardly from one side of the frame which carries a plurality of fingers 10 arranged in spaced relation, a strand of yarn passing upwardly thru the guide loop 8 and over the fingers 10 in frictional contact therewith and thru the guide loop 11 at the upper

end of the rack 12 which supports the fingers 10 and thus thru the guide loop 6.

Attention is directed to the fact that the arm 13 which supports the guide loop 11 is disposed at an acute angle relative to the rack 12 so that when the strand of yarn passes thru the loop 11 it will have a tendency to pass thru one end of the loop 11 as shown in the drawing.

Rockably mounted in the frame 1 within the bearings 13' supported by the arm 9 is a movable arm 14 carrying a rack 15 at its inner end upon which are formed the fingers 16. The fingers 16 are so arranged upon the rack 15 as to be alternately arranged between the fingers 10 of the rack 12 and the position of the rack 15 is such that the same is retained in an upright position by means of the strand of yarn which passes thru the fingers 10 as is shown in the drawing so that should the yarn supply become exhausted the rack 15 will move to a horizontal position rotating the arm 14 and thru its connection 17 with the vertical movable rod 18, cause this rod 18 to drop downwardly, the lower end of the rod 18 engaging a trip 19 which is connected to the regulating mechanism of the machine so that when the trip is actuated by the rod 18 the power will be cut off from the main machine causing the same to stop. The rod 18 carries a stop finger 20 which is adapted to engage one of the bearings 21 for the rod 18 to limit the downward sliding movement of said rod.

From the above it will be apparent that as long as the ribber yarn known as the third yarn on the stocking machine of the ribber type is passing between the fingers 10 and 16 of the racks 12 and 15, the machine will continue to function properly but should the third yarn become broken or the supply exhausted, there will be no further means for retaining the rack 15 in an upright position thus allowing the same to move to a horizontal position thru its own weight, retaining the arm 9 and actuating the rod 18 for cutting off the power of the main machine so that the same will stop.

While I have shown and described the preferred form of my invention, it will be obvious that various changes in the details of construction and the combination and proportions may be resorted to for successfully carrying my invention into practice

without sacrificing any of the novel features or departing from the scope of the appended claim.

Having thus described my invention, what I claim is:

A device of the class described, including a substantially rectangular frame, one of the members of said frame being in the form of a tube, guide members carried by opposite corresponding frame members of said frame through which a plurality of strands of yarn is adapted to pass, a bifurcated guide member carried by one of said corresponding frame members, guide loops carried by the other opposite corresponding frame members, a rack providing a plurality

of spaced fingers, a movable member providing a rack having a plurality of fingers interposed between said first mentioned fingers, and means coacting with the movable member for actuating a trip upon movement of said movable member in a certain direction, the combination with a strand of ~~yarn~~ adapted for passage between the fingers for supporting the movable member against ~~said~~ movement in said certain direction and extending through the loops and the bifurcated member to a downward course through the tube.

In testimony whereof I affix my signature. 30

FELIX BOLINSKI.
